TORPEDO

Harry Luther Boesch, Washington, D. C., assignor
to Government of the United States

Application March 18, 1922, Serial No. 544,943

5 Claims. (Cl. 60—46)

(Granted under the act of March 3, 1883, as
amended April 30, 1928; 370 O. G. 757)

This invention relates to torpedoes and more particularly the valve mechanisms for controlling the flow of fuel and water from their respective compartments to the combustion flask.

In order that a clearer perception of the present invention and the objects sought to be accomplished may be had it may be briefly stated, as is well-known to those familiar with the art, that in the central portion of the torpedo there is located a compressed air reservoir, a fuel compartment and a water compartment, all forward of the bulkhead separating the central part from the after-body of the torpedo. The air, fuel and water are, at the moment of launching, conducted to a combustion flask where the fuel is ignited, combustion being supported by the oxygen of the air and the heat liberated raising the products of combustion and the nitrogen of the air to a high temperature, vaporizing the water and superheating the resulting mixture of gases, which is conducted from the combustion flask and utilized for driving the torpedo engine. With the usual arrangement of air, fuel and water reservoirs or containers it frequently happens that leakage from the high pressure air reservoir causes a rise in pressure in the water compartment, or in the water and fuel compartments, prior to launching the torpedo, causing premature flow of liquids, particularly water, into the combustion flask with resulting serious failures of ignition and combustion.

It is, therefore, one of the objects of the present invention to prevent the accumulation of excessive pressures in the water and fuel compartments and also to provide means whereby the premature or untimely flow of liquids into the combustion flask will be positively prevented, and the admission of these liquids to the combustion chamber definitely controlled in any desired sequence to insure reliable ignition and combustion.

A further object is to provide a simple and practical valve mechanism of the above general character which will be reliable and efficient in use and operation.

Other objects will be in part obvious and in part hereinafter pointed out in connection with the accompanying drawings illustrating the preferred embodiment of my invention wherein like reference characters indicate corresponding parts throughout the several views, and in which

Figure 1 is a side elevation of my valve mechanism,

Figure 2 is a detail of the valve plug,

Figures 3, 4, and 5 are transverse sectional views

on the lines 3—3, 4—4, and 5—5, respectively, of Figure 1.

Figure 6 is an end view of the valve,

Figure 7 is a detail view of the valve plug, similar to Figure 2, but showing an arrangement of the fuel and water ports by which the flow of the liquids may be made to start in sequence,

Figure 8 is a partial longitudinal section of a torpedo diagrammatically showing the application of my invention thereto, and

Figure 9 is a partial cross sectional view of a torpedo showing the various pipe connections to the valve.

Referring more particularly to Figure 1 of the drawings, 10 indicates a main valve casing preferably constructed in one piece and provided with a valve plug shown in Figures 2 and 7. The plug and casing are held in assembled relation by a closure nut 12 at one end and suitable packing members 13 at the other end. The end of the plug stem has an actuating arm 15 secured thereto by a nut or other suitable fastening means 16.

The valve casing 10 is provided on one side with an air inlet port 17 and on the top with air outlet ports 18 and 20 leading respectively through conduits 36 and 37 to the water compartment 34 and fuel compartment 35 of the torpedo. When the port 17 is opened air under pressure is admitted to the water and fuel compartments forcing their contents out through conduits 38 and 39, respectively, to the valve casing through the inlet ports 21 and 22, the former being for the fuel and the latter for the water. After passing through the valve, the fuel and water pass out through ports 23 and 24 and are conducted through conduits 38' and 39' to the combustion flask 40 where they mix with compressed air admitted from the compressed air receptacle 14 through pipe line 41 and subsequent connections.

Previous to launching the torpedo, the valve is in closed position, as shown in Figures 3, 4, and 5; that is, the plug 11 is turned in the casing 10 so as to close the fuel and water inlet ports 21 and 22, and at the same time the air inlet port 17 is closed preventing the passage of air into the fuel and water compartments.

During the inactive period of the torpedo, difficulty has been experienced in preventing air from the charged compressed air receptacle leaking around the bulkhead that separates the receptacle from the rest of the after body of the torpedo. By referring to Figure 8, it will be seen that these points of leak are indicated A and B, respectively. In a short space of time this sep-

age will build up a pressure in the water compartment considerably in excess of the pressure desired therein, and tends to force the contents thereof into the main valve. Likewise, air that 5 has thus passed into the water compartment may in turn seep through the opening in the wall of the fuel compartment for admission of the conduits 37 and 39, and tend to prematurely force fuel into the main valve. Relief valves 25, normally closed by springs 26, permit the expenditure of the undesired accumulated pressure without its having a detrimental effect upon the successful operation of the torpedo. Ports 32 in plug 11, see Figure 2, complete the passageway 10 from conduits 36 and 37 and ports 18 and 20 to the relief valves, the fluid then passing through conduit 27 to port 28, from whence it is directed toward the after body of the torpedo by conduit 47, more clearly seen in Figure 8.

20 When the main valve is opened the relief valves 25 are closed from communication with the fuel and water compartments, the air inlet port 17 is placed in communication with the outlet ports 18 and 20 by means of the port 31 in the valve plug 11, and the fuel and water inlet ports 21 and 22 are placed in communication with the outlet ports 23 and 24 by means of the ports 30 and 33 in the valve plug. Air will now pass in through port 17 and out through the outlets 18 and 20 to the fuel and water compartments forcing the contents thereof to the inlet ports 21 and 22 and through the ports 23 and 24 to the combustion flask, as previously explained.

30 It will be understood that the valve plug may be provided with ports 30 and 33 of the same length, see Figure 2, or of different lengths whereby the proper sequence of flow of fuel and water to the combustion flask may be regulated. This latter construction is illustrated in Figure 7 35 wherein the fuel port 30' is made longer than the water port 33', thereby causing the fuel line to be opened first and fuel delivered to the combustion flask in advance of the water.

40 The operation of the invention can best be understood by referring to Figure 8 wherein 14 is the after portion of the compressed air receptacle, 34 is the water compartment and 35 is the fuel compartment, here shown as a vessel mounted within the water compartment. When the 45 torpedo is started, compressed air flows through the main air pipes 41 and 41' and the stop valve 42 to the starting and reducing valve 43. The main air supply, after being reduced to a suitable and constant working pressure by means of the reducing valve, flows through the conduit 41'' to the combustion flask 40. A portion of the air supply at the reduced pressure is led through conduit 44 to the valve 10 through which it passes and is conducted through conduits 36 50 and 37 to the water and fuel compartments, placing the contents therein under pressure. This pressure, by virtue of certain features of the design of the air passages which do not concern the present invention, is somewhat higher than the pressure in the combustion flask. Under the 55 action of the pressure referred to, the liquids are forced from the water and fuel compartments, through conduits 38 and 39 to the valve 10, and after passing through the valve, are conducted by conduits 38' and 39' to the combustion flask 40, where the fuel is mixed with the air entering through conduit 41'' and ignited. The resulting mixture of gases, consisting of the products of the combustion together with the superheated steam resulting from the evaporation of the in-

jected water, passes through pipe 45 to the main engine 46, here shown as an impulse turbine located in the after body of the torpedo.

Figure 8 also shows how the control arm 15 80 may be connected to a device 48 driven through any suitable means by the torpedo engine whereby the valve may be automatically opened when the torpedo mechanism begins to function. As any suitable gearing may be employed to drive the member 48, it is thought not necessary to show the same in detail.

Figure 9 illustrates a still further manner of operating the valve, either by hand, before it is loaded in the tube, or automatically as it is being loaded in the tube or as it is being launched. 90 In this modification a portion of the operating handle 15 extends beyond the shell of the torpedo where it may be gripped by the hand for manual operation, or where it engages with a suitable lug or latch place within the bore of the tube. The installation of such a lug is so obvious to those versed in the art that it is believed unnecessary to illustrate such construction in detail. It will thus be seen that the present invention provides a reliable and efficient mechanism for regulating and controlling the flow of fuel and water to the combustion flask of a torpedo in proper sequence. It also prevents the building up of excessive pressures in the fuel and water compartments which would otherwise 105 seriously affect the satisfactory run of the torpedo.

Without further analysis, the foregoing will so fully reveal the gist of this invention that others can by applying current knowledge readily adapt 110 it for various applications without omitting certain features that, from the standpoint of the prior art, fairly constitutes essential characteristics of the generic or specific aspects of this invention, and, therefore, such adaptations should 115 and are intended to be comprehended within the meaning and range of equivalency of the following claims.

The invention herein described may be manufactured and used by or for the Government of 120 the United States of America for governmental purposes without the payment of any royalties thereon or therefor.

What I claim is:—

1. In a valve for torpedoes and the like having 125 fuel and water compartments, in combination, an air inlet port communicating with but normally closed from fuel and water compartments, relief valves for permitting the exhaust of high pressure air which may leak to said compartments and inlet and outlet ports controlled by said valve for permitting the fuel and water to pass through said valve to the combustion flask when said valve is opened.
2. In a valve for torpedoes and the like having 130 fuel and water compartments, in combination, an air inlet port communicating with but normally closed from fuel and water compartments, relief valves for permitting the exhaust of high pressure air which may leak to said compartments, inlet and outlet ports controlled by said valve for permitting the fuel and water to pass through said valve to the combustion flask when said valve is opened, said valve mechanism comprising a single valve plug with cutaway portions 135 registering with the inlet and outlet ports opening and closing the same as desired.
3. In a valve for torpedoes and the like having 140 fuel and water compartments, in combination, an air inlet port communicating with but nor-

145 150

- inally closed from fuel and water compartments, relief valves for permitting the exhaust of high pressure air which may leak to said compartments, inlet and outlet ports controlled by said valve for permitting the fuel and water to pass through said valve to the combustion flask when said valve is opened and means for actuating said valves, comprising a crank arm adapted to be actuated either manually or automatically.
- 10 4. In a valve for torpedoes and the like having fuel and water compartments, in combination, a valve casing, a plug having cutaway portions, said valve casing having an air inlet port and outlet ports normally closed and adapted to lead to fuel and water compartments, said casing also having inlet and outlet ports through which the fuel and water are adapted to pass from the compartments to the combustion flask and means
5. In a valve for torpedoes and the like having fuel and water compartments, in combination, a valve casing, a plug having cutaway portions, 80 said valve casing having an air inlet port and outlet ports normally closed and adapted to lead to fuel and water compartments, said casing also having inlet and outlet ports through which the fuel and water are adapted to pass from the compartments to the combustion flask, means for preventing excessive pressure in the fuel and water compartments when said valve is closed.
- 15 to fuel and water compartments, said casing also having inlet and outlet ports through which the fuel and water are adapted to pass from the compartments to the combustion flask and means 85 for preventing excessive pressure in the fuel and water compartments when said valve is closed and means for actuating said valve for opening the ports whereby compressed air enters the 90 compartments and forces the fuel and water therefrom.
